UNITED STATES PATENT OFFICE.

ROLFE RAY HOLBROOK, OF NEW ORLEANS, LOUISIANA, ASSIGNOR TO WILLIAM A. LURIE, OF NEW ORLEANS, LOUISIANA.

KEY-CUTTING MACHINE.

1,400,678.

Specification of Letters Patent. Patented Dec. 20, 1921.

Application filed November 15, 1920. Serial No. 424,014.

To all whom it may concern:

Be it known that I, ROLFE R. HOLBROOK, a citizen of the United States, and a resident of New Orleans, parish of Orleans, 5 State of Louisiana, have invented certain new and useful Improvements in Key-Cutting Machines, of which the following is a specification.

My invention relates to an improved machine for cutting or duplicating keys of the flat type, bitted type, or other type, the object of the invention being to provide simple construction and arrangement which will permit keys to be readily cut by various tools and in various directions without changing the position of the pattern key or the key to be cut. My improved machine is shown on the accompanying drawings in which—

20 Figure 1 is a side elevational view, Fig. 2 is an end elevational view with parts in section, and

25 Fig. 3 is a plan view of the key supporting structure and part of the key cutting mechanism.

A flat base 5 supports intermediate its ends and at its rear edge the bearing frame 6 having the bearing extension arms 7 and 8 in which is journaled the shaft 9, the pulley 10 being secured on the shaft between the bearing arms to be driven by means of a belt 11. At one end the shaft has secured thereto the rectangular slot cutter 12 and at its other end, it has secured thereto the 35 triangular slot cutter 13, the cutters being preferably detachably applied so that different kinds of cutters may be substituted. In front of the bearing frame and at the respective ends of the base 5 are the vertical lugs 14, 15 and 16, 17. Secured in the lugs 14 and 16 is the rail shaft 18 and in the lugs 15 and 17 is secured a similar shaft 19, the shafts being in a common horizontal plane and being parallel with the cutter shaft 9. Pins 20 may be provided for securing the shafts in place. Saddle frames or riders 21 and 22 straddle the shafts 18 and 19 respectively to slide longitudinally thereon, two such frames being shown on 45 each shaft. The saddle frames on the respective shafts are spaced apart, and secured at their ends in the respective saddle frames and extending crosswise of the shafts 18 and 19 are the rail shafts 23 and 24 which

are secured in the saddle frames as by means 55 of pins 25. The shafts 23 and 24 extend through the front and rear walls 26 and 27 which depend from the table 28, the table being thus reciprocable on the shaft at right angles to the shafts 18 and 19, while the 60 table structure together with the cross shafts and the saddle frames is reciprocable longitudinally of the bed plate 5 on the shafts 18 and 19. On top of the table 28 is the base 29 which has the pivot stud 30 extending downwardly therefrom through the hole 30' in the table 28 so that the base 29 is rotatable on the table. A barrel 31 receives the lower end of the stud 30 and contains a compression spring 32, this spring abutting 65 against the head of the barrel and against the nut 33 engaging with the threaded lower end of the stud so that the barrel is held against the under side of the table 28 and the platform 29 held yieldingly down 70 against the top of the table, the barrel extending downwardly between the cross shafts 23 and 24. A lock lever 34 is pivoted at its upper end on the base 20 between the ears 35 and 36 and is adapted to engage 75 between the lugs 37 and 38 extending from the wall 26 in order to lock the base 29 in normal position on the table 28.

Extending upwardly from the base 29 at the center thereof is the pillar 39 having at 85 its upper end and near the front edge thereof a key receiving slot or groove 40 which registers with a similar groove 41 formed in the cap 42 which is held in place on the pillar by means of a screw 43, the pattern key P being 90 shown clamped between the cap and pillar. Guide screws 44 thread through the cap with their lower ends projecting into the pockets 45 which contain compression springs 46. The screws serve to align the cap when it 95 is applied and the springs serve to raise the cap as the clamping screw 43 is withdrawn so that a key may be readily inserted into position to be clamped or be removed.

In front of the pillar 39 is a lower pillar 100 or step 47 which has the groove 48 along its front edge which registers with the groove 49 in the cap 50 to receive a key K to be cut. A screw 51 serves to clamp the cap against the step and guide screws 52 and 105 springs 53 are provided for alining the cap and for raising it when the screw 51 is loosened. The grooves may be of such shape as

to readily accommodate the cylindrical shanks of bitted keys or to accommodate flat keys.

Extending upwardly from the bed plate 5 behind and in alignment with the respective cutters are the pedestals 54 and 55 for supporting the guide fingers 56 and 57, respectively, having their front ends 58 and 59 shaped in conformity with the cutters 12 and 13 mounted at the ends of the shaft 9. As shown, the point 58 is rectangular and the point 59 is triangular. The guide fingers are adjustable on top of the respective standards by means of the set screws 60 and 15 the longitudinal slots 61 formed in the fingers.

Describing now the operation, the drawings show the pattern key P clamped on the pillar 39, the key being an ordinary house key comprising the shank *a* and the bit *b*. On the step 47 is clamped the key K to be cut, the keys being clamped so that their bits are in register. The pattern key has the rectangular slots *c* and therefore the cutter 12 will be used for cutting the key K. After a clamping of the keys in position, the operator sets the finger 56 in the proper position to bring its point 58 vertically above and in the plane of the cutter 12. The table 30 or carriage structure 28 is then shifted laterally on the shafts 18 and 19 to a position which will bring one of the slots of the pattern key in the plane of the cutter, and the carriage is then shifted rearwardly on the shafts 23 and 24 until a slot of the pattern key receives the point 58. The adjustment of the finger is such that immediately after its point receives one of the slots of the pattern key to thereby lock the carriage against 40 longitudinal travel on the bed plate 5, the cutter will engage with and cut the bit of the key K, and as the carriage is fed rearwardly, a slot corresponding to that of the pattern key is cut in the key K, further cutting being prevented when the point 58 of the guide finger reaches the base of the slot of the pattern key. The operator then withdraws the carriage and shifts it laterally to bring the finger point into registration 50 with the next slot whereupon the carriage is shifted rearwardly and the key K cut by the cutter. If it is desired to cut a key with triangular slots, the pattern key and the key to be cut are properly clamped on the carriage structure and the structure shifted into cooperation with the point 59 and guide finger 57 and the carriage shifted rearwardly whereupon the cutter 13 will cut the key in accordance with the pattern key. For 60 any other shape of slot the proper cutter is secured to the shaft 9.

As has been described, the top key supporting structure of the carriage structure is rotatable and held in normal position by the lock lever 34. When the lock lever is

raised, the key supporting part can be turned around into more convenient position for positioning the keys therein. Rotation of this key supporting part also permits the keys to be readily brought into desired angular position with reference to the cutter. It may sometimes be desirable to cut notches in the front edge of the bit of a key and the revolving structure is then rotated 90 degrees one way or the other and the lock lever 70 34 is engaged between the locking lugs 62 or 63 on the opposite side of the table 28. The structure can also be rotated to intermediate positions for finishing or special work and the spring 32 will then serve to 80 hold the key supporting structure sufficiently rigid while cutting is going on.

I thus provide a very simple, efficient and easily manipulated key cutting machine. Changes and modifications can no doubt be 85 made which would still come within the scope of my invention and I do not therefore desire to be limited to precisely what I have shown and described.

I claim as follows:

1. In a machine of the class described, the combination of a rotatable cutter, a key supporting structure, and means for clamping a blank on said structure, said structure being rotatable whereby to adjust said blank at 90 a desired angle with reference to the cutter, said structure being shiftable to carry the blank into engagement with said cutter.

2. In a machine of the class described, the combination of a rotatable cutter, a carriage structure shiftable in front of said cutter, means for clamping a pattern key on said carriage structure and means for clamping a blank key thereon, and a guide finger associated with the cutter for engaging in the 100 slots of the pattern keys to thereby guide the carriage structure to bring the key blanks into proper coöperation with said cutter, said carriage structure being rotatable whereby to bring the keys thereon into desired angles with reference to the cutter.

3. In a machine of the class described, the combination of a rotatable cutter, a carriage in front of said cutter, means for clamping a key blank on said carriage, and means whereby said carriage may be bodily shifted and rotated whereby to bring said blank into desired position with reference to said cutter.

4. In a machine of the class described, the combination of a bed plate, a shaft journaled 120 on said bed plate, a cutter on said shaft, a carriage shiftable longitudinally on said bed plate and transversely thereon in front of said cutter, clamping mechanism on said carriage for receiving a pattern key and a 125 blank key to be cut, a guide finger associated with said cutter for engaging in the slots of the pattern key to thereby control the coöperation of the cutter with the key blank, said clamping mechanism being rotatable 130

whereby to adjust the position of said key with reference to said cutter.

5. In a machine of the class described, the combination of a rotatable cutter, a key supporting structure, means for clamping a blank on said structure, said structure being rotatable and bodily shiftable whereby to adjust the blank with reference to said cutter, and means for locking said structure after 10 rotational adjustment thereof.

6. In a machine of the class described, the combination of a rotatable cutter, a carriage shiftable toward said cutter, a top on said carriage rotatable thereon, and means on 15 said top for holding a key to be cut by said cutter.

7. In a machine of the class described, the combination of a rotatable cutter, a carriage shiftable toward and away from said cutter, 20 a top on said carriage, means on said top for supporting a blank to be cut, said top being rotatable on said carriage whereby to adjust said blank at a desired angle with reference

to the cutter, and means for locking said top after rotational adjustment thereof. 25

8. In a machine of the class described, the combination of a rotatable cutter, a carriage shiftable toward and away from said cutter, a top on said carriage, means on said top for supporting a blank to be cut, said top 30 being rotatable on said carriage, and yielding means frictionally holding said top on said carriage against rotation thereof.

9. In a machine of the class described, the combination of a rotatable cutter, a carriage 35 shiftable toward and away from said cutter, a top on said carriage, means on said top for clamping a blank to be cut, said top being rotatable on said carriage, and a spring for causing said top to be frictionally held on 40 said carriage after a rotational adjustment thereof.

In witness whereof, I hereunto subscribe my name this 3rd day of November, A. D. 1920.

ROLFE RAY HOLBROOK.
